[57] CLAIM

The design of a fiber optic illuminated dental handpiece,
as shown and described.

DESCRIPTION

FIG. 1 is a side elevation of a fiber optic illuminated
dental handpiece, showing my new design.

FIG. 2 is a top plan view thereof.

FIG. 3 is a bottom plan view thereof.

FIG. 4 is a front end elevation thereof.

FIG. 5 is a rear end elevation thereof.

The broken lines are shown for illustrative purposes
only.
